UNITED STATES PATENT OFFICE.

WILLIAM G. BRUNS, OF SIOUX FALLS, SOUTH DAKOTA.

BROODER.

Application filed January 5, 1926. Serial No. 79,335.

This invention relates to an improved brooder adapted more particularly for affording comfort and shelter to small chickens.

5 The invention has more particular reference to that type embodying a hood which is supported above the ground a distance sufficient to permit the small chickens to readily gather therebeneath and huddle together in the customary way, there being a heater provided under the hood for affording warmth for said chickens.

10 My principal aim is to generally improve upon inventions of this class by providing one wherein the heater is effectively housed in a structure which serves to distribute the heat waves and to carry out the gaseous fumes from the burner flame, whereby to eliminate detrimental obnoxious odors beneath the hood.

15 A specific feature of construction is a sectional hood, and supporting means therefor which is associated with the burner housing structure, together with a draft producing and fume conducting conduit.

20 Other features and advantages and novel details of construction will become apparent from the following description and drawings.

25 30 In the accompanying drawings forming a part of this application and in which like numerals are employed to designate like parts throughout the same:

35 Figure 1 is a top plan view of a brooder, constructed in accordance with the present invention.

40 Fig. 2 is a longitudinal sectional view showing the internal construction more plainly.

45 Fig. 3 is a cross section taken through the central portion of the structure to show supporting means for the hood more plainly.

50 Figs. 4, 5, and 6 are fragmentary views in elevation and section, showing the fume stack or conduit, and the damper construction association therewith.

55 Fig. 7 is a fragmentary view of a portion of the structure showing the door equipped side of the burner housing.

Referring to the drawings in detail, the reference character 1 designates generally the hood. This is somewhat pyramidal in configuration and is composed of two duplicate half sections 2 and 3. The hood is open at its bottom and has its lower edge bent

upon itself as indicated at 4 with the extremity disposed on the interior and directed in a horizontal plane as at 5 forming a supporting flange. 60

The apex or top of the hood is flattened somewhat as indicated at 6. Moreover the meeting edges of the two sections are formed with angularly disposed flanges which are fastened together by bolts or the like 7 (see 65 Fig. 1).

Arranged beneath and inside of the hood is a housing structure generally designated by the reference character 8. This comprises a central rectangular casing 9 having 70 its bottom apertured as at 10 to provide air intake openings. This casing constitutes an enclosure for a suitable type of burner indicated at 11. The stack of the burner is represented by the reference character 75 12.

Extending from the top of the cylindrical casing 9 are passages 13 of suitable cross section which connect with depending branches 14. These branches are connected, as indicated at 15, with upstanding conductors 16 which extend upwardly through openings in the flattened apex of the hood. Connected to the projecting upper ends of these conductors are the downturned portions 17 of a U-shaped pipe 18. This pipe 18 carries 80 a vertical conduit 19 at its center. This conduit leads through the roof of the coop or other building in which the brooder is ordinarily located and serves to discharge gaseous fumes from the burner into the atmosphere. 85

It will be noted that the conduit is formed with an opening 20 adjacent its point of connection with the pipe 18. By referring to Figs. 4 to 6 inclusive, it will be seen that a damper plate 21 cooperates with this opening, and the damper plate being hingedly mounted as at 22, provided with an operating shaft 23 and a crank arm 24. The 100 crank arm is connected to an adjusting screw or the like 25 extending upwardly through a bracket 26 and held in adjusted position by a nut 27 thereon. This damper constitutes a draft regulator. 105

In order to space the hood above the ground to afford a space for passage of the small chickens, I provide novel supporting means for said hood. Referring to Fig. 3, it will be seen that the supporting means is 110 designated generally by the reference character 28. The supporting means here shown

comprises a pair of duplicate rods 29, each of which has its central portion connected to the burner casing 9. The end portions extend outwardly beyond the casing and engage the supporting flanges or ledges 5. In addition, there are similar supporting bars 30 and 31 disposed between the parts 14 and 16 (see Fig. 2), and these also engage the supporting flange 5. In this way, the hood is movably supported, and as it is of sectional formation, it is obvious that it may be readily removed for cleaning and repairs.

It is yet to be pointed out that the hood may be provided with a plurality of hinged-
15 ly mounted closures or doors 32 and 33, (see Fig. 1). Also, there is a baffle plate or flame breaker plate 34 disposed in the passages 13 at a point over top of the burner stack 12, (see Fig. 2).

20 Attention is also directed to the fact that the aforesaid burner housing is provided on one side with a pair of hingedly mounted doors, these doors being in turn provided with cooperating latch elements which serve to maintain them normally closed. It is ob-
25 vious, however, that the doors are provided to permit access to be had to the interior of the housing for removing and cleaning the burner.

30 In operation, the flame from the burner impinges against the plate 34 and the particles of combustion and smoke pass through the passages 13, down thru the branches 14 and then up through the conductors 16 and 35 into the discharge pipe 18. From here, they pass out through the conduits and are discharged into the atmosphere. The draft may be regulated by the damper. It is ob-
vious too, that the air is sucked in through

the openings 10 at the bottom of the cas- 40 ing 9.

It is believed that by considering the de-
scription in connection with the drawings, persons skilled in the art to which the in-
vention relates will be able to obtain a clear 45 understanding of the same. Therefore, a more lengthy description is thought unnec-
essary.

While the preferred embodiment of the invention has been shown and described, it 50 is to be understood that minor changes coming within the field of invention claimed may be resorted to if desired.

Having thus described my invention, what I claim as new is:—

55 In a broader of the class described, in combination, a burner, a cylindrical housing surrounding said burner, a conduit connect-
ed with the upper portion of the housing and including branches extending in oppo-
site directions from said housing, said branches including depending portions and upwardly directed portions, supporting
60 members carried by the lower portion of said housing and extending radially there-
from, a sectional hood adapted to enclose
said housing and conduit, said housing includ-
ing a flattened apex portion and down-
wardly inclined side and end wall portions,
65 said apex portion being provided with open-
ings through which the discharge end of the upwardly directed portions of said branches are extended, and a substantially U-shaped
conductor pipe, the end portions of the arms
70 of which are connected with the discharge
end portions of said branches.

In testimony whereof I affix my signature.
WILLIAM G. BRUNS.
